UNITED STATES PATENT OFFICE.

JAMES W. McINDOE, OF MEDFORD, AND ARTHUR E. WHITNEY, OF WINCHESTER,
MASSACHUSETTS.

METHOD OF MAKING WALL-COVERINGS.

1,208,808.

Specification of Letters Patent. Patented Dec. 19, 1916.

Application filed March 22, 1916. Serial No. 86,313.

To all whom it may concern:

Be it known that we, JAMES W. McINDOE, a citizen of the United States of America, and a resident of Medford, in the county of 5 Middlesex and State of Massachusetts, and ARTHUR E. WHITNEY, a citizen of the United States of America, and a resident of Winchester, in the county of Middlesex and State of Massachusetts, have invented certain new 10 and useful Improvements in Methods of Making Wall-Coverings, of which the following is a specification.

This invention relates to methods of applying designs to sheets of material such as 15 board, wall board, wall paper, etc., and has for its object the provision of means whereby an inexpensive sheet of material may be readily provided with an ornamental configuration which will greatly increase its 20 value.

It is particularly adapted for use in the manufacture of wall coverings either in the form of paper to be secured to the plastered wall or in the form of wall board to be secured directly to the studding of the building.

Any selected article having a flat face and provided with a suitable configuration may be used and by means of this improved 30 method may be transferred to sheets of material in exact reproduction of the original. For instance, a wood veneer may be used and the grain thereof transferred to a sheet of wall board so exactly that after the board 35 has been stained it is impossible to distinguish by eye the counterfeit from the original.

The invention consists in certain novel methods whereby these desirable results are 40 obtained, all of which will be readily understood by reference to the description of the drawings and to the claims to be hereinafter given.

Of the drawings: Figure 1 represents a 45 plan of two abutting pieces of wood from which it is desired to reproduce the grain on some other material. Fig. 2 represents an elevation of the same secured to a supporting plate, said plate being shown in section. Fig. 50 3 represents a similar view showing in eleva-

tion superimposed upon the face of said abutting pieces of wood an electroplate thereof. Fig. 4 represents a plan of said electroplate. Fig. 5 represents an edge view of the same formed into a cylinder. Fig. 6 represents a plan of said cylinder. Fig. 7 represents an elevation of a forming cylinder adapted to contain said electroplate. Fig. 8 represents an end elevation of the same. Fig. 9 represents a transverse section of the same, on line 9—9 on Fig. 7, and showing the reinforce for said electroplate. Fig. 10 represents a longitudinal section of the completed impression cylinder with said electroplate forming the periphery thereof. Fig. 11 represents an end elevation of the same. Fig. 12 represents a longitudinal elevation of the same, partially in section, and showing the impression cylinder separated from its supporting mandrel. Fig. 13 represents a longitudinal section of an electrotype bath in which the forming cylinder is agitated endwise while the copper reinforce is being formed on the inner face of the electroplate, said section being on line 13—13 on Fig. 14. Fig. 14 represents a transverse section of the same on line 14—14 on Fig. 13. Fig. 15 represents an elevation partially in section of the apparatus used to heat the reinforced electroplate preparatory to the formation 80 of the lead backing therefor. Fig. 16 represents a section of one end thereof moved into vertical position and showing the funnel through which molten lead may be poured in the formation of the backing for 85 the electroplate. Fig. 17 represents an elevation of said heater. Fig. 18 represents a horizontal section of the revoluble electroplate support on line 18—18 on Fig. 16. Fig. 19 represents a plan of a machine in 90 which sheets of material may be subjected to the impressions of the electroplate cylinder. Fig. 20 represents a longitudinal section of the same. Fig. 21 represents an elevation of the mechanism for feeding the material and applying a filler to the indentations formed therein by said impression cylinder. Fig. 22 represents a sectional detail showing the material passing between the 95 filler roll and supporting roll. Fig. 23 rep- 100

resents a face view of a piece of wall board on which a design has been impressed by this new method. Fig. 24 represents a transverse section of the same before passing beneath 5 the impression cylinder. Fig. 25 represents a similar view of said board after passing beneath the impression cylinder. Fig. 26 represents a similar view showing the indentations formed in the face thereof filled 10 with material of a different shade or color, and Fig. 27 represents a longitudinal sectional detail of said board showing a single filled indentation.

Similar characters designate like parts 15 throughout the several figures of the drawings.

In the drawings, 30, 31 are two pieces of wood or wood veneer, the grain in one of 20 which is just the reverse of that in the other. The corresponding ends of these pieces of material are trimmed and then the trimmed edges are butted against one another as at 25 32, Fig. 1 and secured to a flat supporting plate 33 by means of shellac or some other adhesive substance. Preferably the flat plate 33 is of metal and the pieces of material 30, 31 should be of equal thickness throughout. When these pieces of material 30, 31 have been secured in position with 30 two ends abutting at 32, a continuous design is formed, the lines of grain in one piece 30 meeting the lines of grain in the other piece 31. When the pieces 30, 31 have been immovably secured in position upon 35 the plate 33 the upper surfaces of these pieces are smoothed and leveled in any well-known manner, and then soaked in some substance, such as turpentine, until the gum in the grain is thoroughly softened. After 40 the gum has been softened sufficiently it is removed from the grain, this operation preferably being effected by a wire brush. The material will then have in its upper surface a plurality of cavities from which the 45 gum has been removed.

When the material has become dry a thin coating of shellac is applied to the entire upper surface, including the cavities therein, and when this shellac has become dry, 50 powdered graphite or some similar electric conductor is deposited over the entire upper surface as indicated at 34 in the lower left hand corner of Fig. 1.

The plate 33 with the pieces of material 55 30, 31 thereon is then placed in an electroplate bath and a positive electroplate 35 is formed thereon and then stripped therefrom. The outer ends of the electroplate 35 are then trimmed on the parallel lines 36 60 which must be equidistant from the center of the design so that when bent into the form of a cylinder as shown in Figs. 5 and 6, the lines of the grain at one end will be directly opposite the lines of the grain at the

opposite end as shown in Fig. 6. The bent 65 electroplate 35 is then placed within a forming tube 37 (Figs. 7, 8, and 9) with its printing surface against the inner wall of the tube. The tube 37 is split from end to 70 end and provided with ears 38 which extend over the space between the opposed ends and serve to insure the proper register of the edges when they are drawn together into the position shown in Fig. 9 in which position the ends 36 of the electroplate 35 75 will also abut. The tube 37 is provided with a plurality of radial projections 39 in which are mounted the threaded adjusting bolts 40 having the nuts 41 mounted thereon. Normally the split tube 37 is in the position 80 shown in Fig. 8, but when the nuts 41 are turned on the bolts 40 it may be sprung into the position shown in Fig. 9 in which position its interior wall will be a perfect cylinder against which the printing face of the 85 electroplate 35 will contact.

The outer face of the electroplate 35 is covered with oil, grease, or some other non-conductor to prevent any deposit thereon when subsequently placed in an electroplate 90 bath.

The ends of the tube 37 are provided with a plurality of holes 42 adapted to receive the projecting members 43 on supports 44 depending from a frame 45 adapted to be 95 reciprocated by a power driven device 46. The frame 45 is mounted upon rollers 46* revolubly mounted at the upper end of the tank 47 containing the electroplate bath. The construction and operation of the 100 devices used in the electroplating operation need not be described herein, as specifically they form no part of the present invention.

When the tubes 37 with the electroplate 35 therein have been placed in the electroplate bath and the current has been turned on, copper will be deposited on the back of the electroplate 35 thus forming a reinforce 42* therefor. The tubes 37 are reciprocated with the frame 45 and by this 105 means the liquid in the tank 47 is caused to flow through the tube 37 and an even deposit of copper reinforce is insured throughout the length of said tube. When the electroplate 35 has been provided with a reinforce of copper of sufficient thickness to give it rigidity it is removed from the tank 46 and placed between two heads 48 mounted upon a tapered arbor 49 centrally disposed relatively thereto.

As will be seen by referring to Fig. 15 there is considerable space between the arbor 49 and the inner wall of the reinforced electroplate 35. Between the heads 48 is a cylinder 50 of thin sheet metal which protects the electroplate 35 from injury while being subjected to the heat from the charcoal fire built upon the grate 51 at the bot- 120 125

tom of the receptacle 52. The arbor 49 is located above the grate 51 and has trunnions 53 supported on rollers 54 on which they are rotated by the pulley 55.

5 When the electroplate 35 has been sufficiently heated the receptacle is tilted into the position shown in Figs. 16 and 17, the combustibles on the grate 51 first having been dumped. A funnel 56 is then inserted 10 through the opening 57 in one end of the receptacle 52 and through an opening 58 in a head 48 and then molten lead or other soft metal is poured through the same until the space between the electroplate 35 and arbor 15 49 has been completely filled and a solid backing 59 for the electroplate 35 has been created. The reinforced electroplate with its backing 59 is then removed from the arbor 49 and placed upon a tapered arbor 60 of a 20 pressure machine such as is shown in Figs. 19, 20, and 21, said machine being provided with a bed roll 61 between which and the impression roll 60 the sheet of material 62 is adapted to be fed as shown in Fig. 20.

25 The tapered arbor 60 is provided with the flanged ends 63-64 having annular bearing members 65-66 therein and each flange 63-64 is provided with a plurality of threaded members 67 acting upon the bearing members 65-66 and by which the reinforced electroplate 35 with its backing 59 may be forced on or off of the tapered arbor 60.

As the material moves in the direction of 35 the arrow *a* (Fig. 20) the projections on the electroplate 35 will form indentations 68 in the upper face of the material, and as the material passes beneath the roller 69 these 40 indentations will be filled by material of a different shade from the body of the material and thereby bring out with greater clearness the grain of the wood. The filler material is applied to the roller 69 by the distributing device 70.

45 When the sheet of material 62 has passed from beneath the impression cylinder 60 and filler roll 69 it will have impressed in its face the exact reproduction of the grain in the original pieces of wood; as indicated 50 at 71 in Fig. 23. The sheet of material may be as shown in Fig. 24 composed of pulp board with a facing 72 of paper or other substance on one or more surfaces or the impressions may be made in the paper itself 55 or in the pulp board without a facing of other substance.

It is obvious, also, that the impressions may be made in cheaper grades of wood and by selecting veneers of mahogany the grain 60 thereof may be transferred into boards of pine or some other equally inexpensive wood.

The indentations will extend into the surface different distances and have differ-

ent widths and variations in exact imitation of the original grain, and when these indentations have been filled as indicated at 65 73 in Fig. 26, the various thicknesses of the filler will cause the cheaper wood to have the appearance of the more expensive wood used 70 as an original.

In the disclosed embodiment of this invention, pieces of wood are shown and described as the selected pieces of material to be used as originals, but it is self-evident 75 that the process may be carried out with many other kinds of material without departing from the principles of the invention.

While in order to properly describe the invention certain constructions of devices 80 are shown which may be used in carrying out the improved process, it is self-evident that other constructions of said devices may be used equally as well.

Heretofore the greatest difficulty has 85 been found in obtaining an impression roll which will be perfectly cylindrical in cross section, but by this improved process this result is attained, it being apparent that when the electroplate 35 is bent into the 90 forming tube it will spring outwardly with its operating face in contact with the inner wall of said tube, and when the reinforce 42^x has been deposited on its rear face the cylindrical formation thereof is made permanent. 95

It is believed that the many advantages of a process such as is herein described and claimed will be fully apparent without further description.

Having thus described our invention, we 100 claim:

1. The method which consists in taking two pieces of wood veneer of similar design; abutting the ends together with the backs thereof secured to a flat plate; removing the 105 gum from the grain; forming an electroplate therefrom; and then forming said electroplate into an impression cylinder.

2. The method which consists in taking two pieces of wood veneer of similar design; trimming the corresponding ends thereof to produce abutting walls; abutting the trimmed ends together with the backs thereof secured to a flat plate; removing the gum 115 from the grain; forming an electroplate therefrom; and then forming said electroplate into an impression cylinder.

3. The method which consists in taking two pieces of wood veneer of similar design; abutting the ends together with the backs 120 thereof secured to a flat plate; smoothing and leveling said veneer; removing the gum from the grain; forming an electroplate therefrom; and then forming said electroplate into an impression cylinder.

4. The method which consists in taking two pieces of wood veneer of similar design; abutting the ends together with the backs 125

- thereof secured to a flat plate; smoothing and leveling said veneer; giving the surface a light coating of shellac; removing the gum from the grain; forming an electroplate 5 therefrom; and then forming said electroplate into an impression cylinder.

5. The method which consists in taking two pieces of wood veneer of similar design; abutting the ends together with the backs 10 thereof secured to a flat plate; removing the gum from the grain; depositing an electric conductor on the surface; forming an electroplate therefrom; and then forming said electroplate into an impression cylinder.

15 6. The method which consists in taking two pieces of wood veneer of similar design; abutting the ends together with the backs thereof secured to a flat plate; removing the gum from the grain; forming an electroplate 20 therefrom; trimming said electroplate; shaping said electroplate into a cylinder with its printing face outward; and then providing said electroplate cylinder with a solid backing.

25 7. The method which consists in taking two pieces of wood veneer of similar design; abutting the ends together with the backs thereof secured to a flat plate; removing the gum from the grain; forming an electroplate 30 therefrom; trimming said electroplate; shaping said electroplate into a cylinder with its printing face outward; depositing copper by electrolysis on the back of said electroplate cylinder; and then providing said electro- 35 plate cylinder with a solid backing.

8. The method which consists in taking two pieces of wood veneer of similar design; abutting the ends together with the backs thereof secured to a flat plate; removing the 40 gum from the grain; forming an electroplate therefrom; trimming said electroplate; shaping said electroplate into a cylinder with its printing face outward; and then providing said electroplate cylinder with a solid back- 45 ing of soft metal.

9. The method which consists in taking two pieces of wood veneer of similar design; abutting the ends together with the backs thereof secured to a flat plate; removing the 50 gum from the grain; forming an electroplate therefrom; trimming said electroplate; shaping said electroplate into a cylinder with its printing face outward; providing said electroplate cylinder with a solid backing; heating 55 said electrotype cylinder; and then providing said cylinder while heated with a solid soft metal backing.

10. The method which consists in taking two pieces of wood veneer of similar de- 60 sign; abutting the ends together with the backs thereof secured to a flat plate; removing the gum from the grain; forming an electroplate therefrom; trimming said electroplate; shaping said electroplate into a

cylinder with its printing face outward; 65 submerging said cylinder in an electrotype bath; agitating said cylinder in said bath while copper is being deposited on the inner face of said electroplate cylinder; and then providing said electroplate cylinder with 70 a solid backing.

11. The method which consists in taking two pieces of wood veneer of similar de- 75 sign; abutting the ends together with the backs thereof secured to a flat plate; removing the gum from the grain; forming an electroplate therefrom; trimming said electroplate; shaping said electroplate into a longitudinally split cylinder with its printing face outward; forcing together the longitudinal edges of said cylinder to cause the ends of said electroplate to abut; and then providing said electroplate cylinder with a solid backing.

12. The method which consists in taking two pieces of wood veneer of similar design; abutting the ends together with the backs thereof secured to a flat plate; removing the gum from the grain; forming an electroplate 80 therefrom; trimming said electroplate; and then shaping said electroplate into a cylinder with its printing face outward.

13. The method which consists in taking a flat article provided with a configuration; 85 securing said article to a flat plate; depositing an electric conductor over the exposed surface of said article; forming an electroplate therefrom; trimming said electroplate; forming said electroplate into a cylinder with its printing face outward and with the lines of said configuration registering at its abutting ends; and then providing said cylinder with a solid tubular backing.

14. The method which consists in taking a piece of wood; securing said piece of wood to a flat plate; removing the gum from the grain on the exposed face of said wood; depositing an electric conductor over the exposed surface of said piece of wood; and then forming an electroplate therefrom.

15. The method which consists in taking a selected flat article provided with a configuration; securing said article to a flat 95 plate; depositing an electric conductor over the exposed surface of said article; forming an electroplate therefrom; trimming said electroplate; forming said electroplate into a cylinder with its printing face outward; and then providing said cylinder with a copper reinforce deposited upon its rear surface.

16. The method which consists in taking a selected flat article provided with a configuration; securing said article to a flat plate; depositing an electric conductor over the exposed surface of said article; form-

ing an electroplate therefrom; trimming said electroplate; forming said electroplate into a cylinder with its printing face outward and the lines of said configuration registering at its abutting ends and then providing said cylinder with a solid backing having a tapered bore.

Signed by us at Boston, Mass., this 24th day of February, 1916.
